UNITED STATES PATENT OFFICE.

FRANZ BRÜCKMANN, JR., AND OTTO DEMPEWOLF, OF BRUNSWICK, GERMANY.

APPARATUS FOR FLANGING, CRIMPING, OR OTHERWISE SHAPING SHEET-METAL BLANKS.

No. 895,067.

Specification of Letters Patent.

Patented Aug. 4, 1908.

Application filed November 27, 1907. Serial No. 404,141.

To all whom it may concern:

Be it known that we, FRANZ BRÜCKMANN, Jr., engineer, and OTTO DEMPEWOLF, locksmith, subjects of the Emperor of Germany, residing at Brunswick, Duchy of Brunswick, Empire of Germany, have invented certain new and useful Improvements in Apparatus for Flanging, Crimping, or Otherwise Shaping Sheet-Metal Blanks, of which the following is a specification.

This invention relates to improvements in apparatus for flanging, crimping, or otherwise shaping sheet metal blanks, in which apparatus the blank is to be worked in successive steps over the whole length of its edge. And the object of the improvements is to provide an apparatus of this class which allows of a continuous operation of the apparatus during all the steps of working the blank, without necessitating the removal of the same from one shaping tool to the next one. And for this purpose, a shaping tool is provided in the improved machine comprising all the sectional tools required for working the blank from the beginning to the end, when the object is completed, which sectional tools come successively and automatically into operation on the blank, while the latter always remains mounted on the same support.

In the example illustrated in the drawings, the various tool-elements are successively formed on the circumference of a disk adapted to be rotated in proximity to the blank holder, so that by the rotation of the disk, each sectional tool is successively brought into operation on the blank.

The invention also consists in certain details of construction, whereby the usefulness of the improved apparatus is increased, and a continuous operation of the same is obtained.

For the purpose of explaining the invention, several examples embodying the same are illustrated in the accompanying drawings, in which—

Figure 1 is a diagrammatical view of the tool and the blank holder showing the various tool elements formed on the circumference of the said tool, Fig. 2, is a plan view of Fig. 1, part of the tool being broken away, and showing, how the said tool and holder coöperate to fold the ends of a can body, the

first step of the operation being shown in the said figure, in which the can body has just been placed on its support, Fig. 3, is a partial plan view similar to that of Fig. 2, showing the second step of the operation of the tool on the can body, Figs. 4 and 5, are views similar to that of Fig. 3, showing further steps in the operation of the tool on the blank, Fig. 6, is a view similar to that of Fig. 1, showing a modification of the apparatus, in which the tool does not directly act on the blank, but through the intermediary of a roller. Fig. 7, is a view similar to that of Fig. 1, and showing, in addition, means for automatically feeding the blanks to the apparatus, Fig. 8, is a plan of Fig. 7 and Fig. 9 is a side view of Fig. 7.

The same letters of reference have been used in all the views to indicate corresponding parts.

In the drawings, an apparatus is shown, which is particularly adapted for use in providing can bodies *a* with a flange *b* (Fig. 5). The can body is, for this purpose, placed on a holder *c* adapted to be rotated, as is usual in the art, which holder will be designated as a spinning holder. The said holder comprises two disks adapted to contact with the inner surface of the can body at places opposite shaping tools *d* coöperating therewith. The said tool consists of a disk *d* the circumference of which is formed with sectional shaping surfaces *d*², *d*³, *d*⁴, the length of each of said surfaces being equal to, or slightly larger than the circumference of the tubular blank *a*, and each of the die surfaces is designed to perform one step in the operation of flanging the blank, as will readily appear from Figs. 3, 4 and 5, the whole operation, in this example, being completed in three steps. A further surface section *d*¹ is provided on the circumference of the disk, which can not act on the blank, but is designed to allow of removing a finished blank and inserting a new one. The length of the said section is equal to that of the other sections, so that the circumference of the disk *d* is four times that of the tubular blank, or a little more than that.

The disks *d* are secured to a shaft *e* supported in suitable brackets of the machine, and provided at opposite ends with spur gears *g*, *g*¹ engaging corresponding spur gears

2
h, h of shafts *c¹, c¹* supporting the spinning blank holders *c*. The disks *d, d* and the holders *c, c* may be rotated in any desired way, a hand wheel *f* being provided in the example illustrated.

5 As stated, while the first section *d¹* is opposite the blank holder *c*, no flanging action takes place as shown in Fig. 2. The radius of the second section *d²* is so much larger than 10 that of the first section, as to perform the preliminary flanging operation on the blank (Fig. 3), the said operation extending over the entire circumference of the blank *a*, because the length of the section *d²* is equal 15 to the circumference of the blank. When the preliminary operation is thus completed, the third section *d³* having a further increased radius comes into action, whereby the flanging operation is continued, as shown in Fig. 20 4, which operation again extends over the entire circumference of the can blank. At last, the section *d⁴* comes into operation, whereby the flange of the can is completed, as shown in Fig. 5.

25 The shaft supporting the disk *d* is so connected with the shaft of the holder *c*, that the latter, at the end of each complete rotation of the disk *d* and while the section *d¹* is opposite the holder, is automatically moved away 30 from the disk *d* and back again, so that the completed blank may fall off the holder, and a new tubular blank may be placed on the same. To show what may be done for this purpose, the shafts *c¹, c¹*, Figs. 7, 8 and 9 are 35 each provided with flanges *c²* having a projection formed on their circumference, which is engaged by a rocking lever *m*. The latter is engaged by a cam groove formed on the circumference of a cam disk *i* rigidly secured to the shaft *e*, which cam groove by 40 means of an intermediary ring *m'* rocks the lever *m* each time the section *d¹* is opposite the holder *c*, so that the latter is moved out of the blank *a* and allows the same to fall 45 down on supports *k* which have been moved inwardly by means of the levers *m*, with which said supports are connected. For increasing the output of the machine, an automatic feeding device may be provided, where- 50 by a new blank is supplied, whenever a completed one slips off the holder. For this purpose a chute *l* is provided receiving the blanks, which are held in position by the blank supported on the holder. If the latter 55 drops its blank down to the supports *k* which are moved together by the levers *m* simultaneously while the disks *c* are separated, a new blank rolls down on the chute *l* while the disks *c* are still separated. This new blank 60 is held upon the flanges *b* of the finished blank which rests upon the supports *k* (Fig. 9), and between the circumferences of the disks *d* and the next blank lying in the chute *l*, in such position relatively to the separated 65 disks *c*, that the said disks *c* may be moved

together and into the new blank, by means of the cam groove *i* when the shaft *c* is further rotated. The operation of the machine is thereby rendered entirely automatic.

If it is desired to have the tool work not 70 only by pressure, but also by friction, so as to grind the blank, the surfaces of the holder *c* and the disk *d* are operated at different speeds.

While, in the foregoing, for the purpose of 75 explaining the invention, the various tool sections are shown as being formed by varying the radius of the disk *d*, the invention is not limited to this particular structure, but the said sections may also be formed in 80 different ways, for instance, by varying the breadth of the disk *d*.

Instead of having the disk *d* act directly on the blank *a*, a swinging disk *n* may be interposed between the said disk and the blank, 85 as shown in Fig. 6, which disk *n* is moved towards and from the blank by the disk *d* according to the radius of its various sections *d¹* to *d⁴*, and thereby exerts the flanging pressure on the blank. 90

Claims:

1. In an apparatus of the character described, the combination with a holder for the blank, of a shaping tool comprising a plurality of rigidly connected tool elements, 95 arranged in an immovable relation to each other, and adapted to perform successive steps in working the blank, and means for moving the said elements.

2. In an apparatus of the character described, the combination with a holder for the blank, of a disk having sections of its circumference successively made with increasing radii, and means for rotating the disk. 100

3. In an apparatus of the character described, the combination with a disk shaped holder for the blank, of a disk having sections of its circumference successively made with increasing radii, a swinging shaping element 110 located in contact with said sections of the circumference of the disk and adjacent to said holder, and means to rotate said holder and disk.

4. In an apparatus of the class described, 115 the combination with a holder for the blank, of a shaping tool comprising a plurality of rigidly connected tool elements, arranged in an immovable relation to each other, and adapted to perform successive steps in working the blank, and means for moving the holder in or out.

5. In an apparatus of the character described, a holder for the blank, a shaping tool, and a support on which a shaped blank is 125 adapted to rest in such a position as to temporarily carry the next blank.

6. In an apparatus of the character described, a movable holder for the blank, a shaping tool and a movable support on 130

which a shaped blank is adapted to rest in such a position as to temporarily carry the next blank, and mechanism for moving the holder to operative position and simultaneously moving the support to its releasing position and vice versa.

In testimony whereof we have hereunto

set our hands in presence of two subscribing witnesses.
